Redmond.

UNITED STATES PATENT OFFICE.

HARRIET LYONS REDMOND, OF BOSTON, MASSACHUSETTS, ASSIGNOR TO THE WILLIAM CARTER COMPANY, OF NEEDHAM HEIGHTS, MASSACHUSETTS, A CORPORATION OF MASSACHUSETTS.

INFANT'S BAND.

1,425,898.

Specification of Letters Patent. Patented Aug. 15, 1922.

Application filed June 7, 1921. Serial No. 475,808.

To all whom it may concern:

Be it known that I, HARRIET LYONS REDMOND, a citizen of the United States, and a resident of Boston, in the county of Suffolk and State of Massachusetts, have invented an Improvement in Infants' Bands, of which the following description, in connection with the accompanying drawings, is a specification, like characters on the drawings representing like parts.

This invention relates to infants' bands and particularly to infants' bands for use in cases of umbilical hernia or like difficulties.

15 In order that the principle of the invention may be readily understood, I have disclosed a single embodiment thereof in the accompanying drawing, wherein,—

Fig. 1 is a front elevation of the band in 20 its folded condition with the ends attached;

Fig. 2 is a similar view of the band viewed from the back;

Fig. 3 is a plan view of the band when 25 it is opened out or unfolded and looking at the inner face thereof;

Fig. 4 is a view similar to Fig. 3, but viewing the band from the outer face thereof; and

30 Fig. 5 is a transverse sectional view taken through the band in its folded condition.

Referring more particularly to the drawings, the band in its entirety is represented at 1. It may be of any suitable material 35 but it is preferably knitted, and desirably the wales 2 extend lengthwise of the band so that the band has but little elasticity or stretch endwise but is relatively elastic transversely.

40 The band may be provided with any suitable means for securing it in position after it has been wrapped about the infant, but in the present instance I have shown a single safety pin 3 and a series of safety pins 4, 45 the former being to attach the end 5 of the band to the body portion thereof at a suitable point, and the series of pins 4 being provided to secure the end portion 6 to the body in a manner that will be set forth more 50 fully hereinafter. If desired buttons and button holes may be used instead, or tapes may be provided, but I prefer to use the safety pins or like fastening devices 3 and 4.

In the present embodiment of my inven-

tion and as clearly indicated in Figs. 3 and 55 4, the band is formed with a zone or area 9 of uniform width which forms the frontal portion of the band, covering the abdomen when the band is adjusted to the body. To one side of said zone 9, shown as the right 60 side in Fig. 3, the relatively long side or end portion 5 tapers slightly toward its outer extremity, while at the other side of said zone 9 the relatively short side or end portion 6 is of uniform width but of slightly 65 less transverse dimension than the frontal zone 9. In this manner I substantially reduce the quantity of material employed, the short side rendering the band less bulky and more readily applied.

70 Desirably the band is reinforced or protected at the edge 7 throughout its entire extent in any suitable manner as by seaming or a similar sewing operation. In this manner the edge of the band is of substantially the same degree of elasticity as the body of the band.

75 At a suitable point, and desirably near the end 6, there is provided a slit 8 extending desirably from nearly the upper to nearly 80 the lower edge of the band, as clearly indicated in Fig. 3. The extent of the slit may be varied within the scope of my invention, but it should be such as to permit the opposite end 5 of the band to be passed 85 through the slit, as clearly indicated in Figs. 1 and 5. Desirably the edges of the material at the slit 8 overlap each other, as most clearly indicated in Fig. 5, so as to provide a reinforcement at the ends of the 90 slit where the stitching 7 occurs, and also to provide a double thickness of material for the reception between them of the inserted end 5 so that the several pins 4 are 95 passed through three thicknesses of material, all as clearly appears from Figs. 1 and 5. Because of this construction there is no liability or danger of tearing the band where the pins 4 are used and the band lies smooth against the body.

100 The features of the invention thus far described are of general application and may be used with bands for other purposes. The other features of the band relate to its use in cases of umbilical hernia or like 105 troubles. For that purpose I provide a pocket in the band at a suitable point and desirably along the zone or area 9, as indi-

cated most clearly in Fig. 3. Herein for the purpose I have secured to the band from near its upper to its lower edge a piece of material 10 seamed or stitched thereto along 5 the lines 11—12 and also along the transverse line 13, the material 10 being left unattached along the line 14, thus providing a pocket 15. The edge 14 of the pocket may have a binding similar to that indicated at 10 7. The pocket 15 is adapted to receive cotton batting, and if desired a piece of metal of suitable size and weight, perhaps about the size of a silver dollar or half dollar, that will rest upon the navel in a manner 15 that will be readily understood.

The band can be secured as tightly as desired since the several pins 3 and 4 may be inserted at suitable points and thus the band tightly binds the infant and serves its intended function.

The band is intended to be placed next the skin, beneath the usual shirt or undergarment and it is not intended to have the diaper or any part attached to it. Thus it 20 25 does not become displaced and is not open to the objections that arise in the case of a band forming a part of or attached to the shirt or undergarment and to which the diaper is intended to be attached.

Having thus described one illustrative embodiment of my invention, I desire it to be understood that although specific terms are employed they are used in a generic and descriptive sense and not for the purpose of 30 35 limitation, the scope of the invention being set forth in the following claims.

Claims:

1. An infant's or like band having near one end only a transversely extending slit, 40 the walls of which overlap to provide extra reinforcing thickness and through which slit the opposite end of the band is adapted to be passed, and fastening means extending through said opposite end and both walls 45 of the slit whereby tearing of the band by said fastening means is prevented.

2. An infant's band composed of knitted material having the wales extending lengthwise the band, the latter having near one 50 end only a transverse slit with overlapping walls and through which slit the opposite end of the band is adapted to be passed, fastening means adapted to pass through the inserted end and both walls of the slit 55 whereby said means is firmly held and tearing of the band is prevented, fastening

means for the opposite end of the band, and a pocket on the inner face of the band, and near said opposite end, said pocket being adapted to receive cotton batting or other 60 material to rest against the part to be treated.

3. An article of manufacture, a combined band and binder adapted for use on infants, comprising a strip of knitted material having a zone of uniform width, side portions of unequal length, the longer side portion tapering slightly toward its outer extremity, the other side portion being of slightly reduced but uniform width, said latter portion having a transverse slit with overlapping edges extending from nearly the upper to nearly the lower edge of the band, and a substantially rectangular piece of material secured to the inner face of said zone to form a pocket adapted to receive cotton batting or other material to rest against the part to be treated.

4. An infant's or like band composed of knitted material having the wales extending 80 lengthwise the band, the latter having at one side of the transverse median line of the band a zone of uniform width, and having side portions of unequal length, the shorter side portion being of slightly reduced but uniform width, the other tapering slightly substantially throughout its length, said band having a transverse slit at approximately mid length of said shorter side portion and through which slit said tapering portion is adapted to be passed, means for securing the parts of the band together at said slit, and a pocket of knitted material seamed to the inner face of said zone and adapted to receive cotton batting or other material 95 to rest against the part to be treated.

5. An infant's or like band formed of knitted material and having a frontal portion 9 of uniform width, side portions 5 and 6 of unequal length at either side of 100 said frontal portion, and a substantially rectangular pocket 15 secured by seams 11, 12, 13 at its sides and bottom to the inner face of said frontal portion 9, said side seams 11 and 12 extending transversely of 105 the band from its upper to its lower edge whereby said pocket is prevented from being torn from the band.

In testimony whereof, I have signed my name to this specification.

HARRIET LYONS REDMOND.
